UNITED STATES PATENT OFFICE

MARGUERITE BRUNSWIG, OF LOS ANGELES, CALIFORNIA

DESIGN FOR A DIAL FOR TIMEPIECES

Application filed May 23, 1932. Serial No. 43,870. Term of patent 3½ years.

To all whom it may concern:

Be it known that I, MARGUERITE BRUNSWIG, a citizen of the United States, residing in Los Angeles, in the county of Los Angeles and State of California, have invented a new, original, and ornamental Design for a Dial for Timepieces, of which the following is a specification, reference being had to the accompanying drawing, forming part thereof.

The figure is a face view of a dial for timepieces showing my new design, the same being of negligible thickness.

I claim:

The ornamental design for a dial for timepieces, as shown and described.
